UNITED STATES PATENT OFFICE.

WINFIELD SCOTT WATSON, OF MEMPHIS, TENNESSEE.

AUTOMATIC BUTTON CUTTING AND SHAPING MACHINE.

No. 897,691.

Specification of Letters Patent.

Patented Sept. 1, 1908.

Application filed July 5, 1907. Serial No. 382,260.

To all whom it may concern:

Be it known that I, WINFIELD SCOTT WATSON, a citizen of the United States, and a resident of Memphis, in the county of Shelby and State of Tennessee, have invented a new and Improved Automatic Button Cutting and Shaping Machine, of which the following is a full, clear, and exact description.

The invention relates to the art of button making such as disclosed, for instance, in the Letters Patent of the United States, No. 831,393, granted to me on September 18, 1906, in the application for Letters Patent of the United States for an automatic button cutting and shaping machine, Serial No. 324,643, filed by me on July 3, 1906, and in the application for Letters Patent of the United States, for a cutting and facing tool, Serial No. 352,738, filed by me on January 17, 1907.

The object of the present invention is to provide a new and improved automatic button-cutting and shaping machine, arranged to automatically cut and dress the face of the button and at the same time sever it from the shell; to prevent the button from sticking in the cutting tool by using the facing tool as a punch while sliding the cutting tool up on the facing tool; and to allow of convenient and quick removal of the worn out or dull cutting and facing tools and replacing the same by proper ones while the machine is running.

The invention consists of novel features and parts and combinations of the same, which will be more fully described hereinafter and then pointed out in the claims.

A practical embodiment of the invention is represented in the accompanying drawings forming a part of this specification, in which similar characters of reference indicate corresponding parts in all the views.

Figure 1 is a side elevation of the improvement, the base being shown in section and the several parts being at rest in lowermost positions; Fig. 2 is a front elevation of the same, and showing the parts in position for cutting the shell; Fig. 3 is an enlarged sectional front elevation of the chuck and the tools carried thereby; Fig. 4 is a sectional plan view of the same on the line 4—4 of Fig. 3; Fig. 5 is a similar view of the same on the line 5—5 of Fig. 3; Fig. 6 is an inverted plan view, partly in section, of the device for holding and releasing the tools; Fig. 7 is a like view of the same showing the parts in a different position; Fig. 8 is an enlarged front elevation of the improvement showing the

parts in a raised position; Fig. 9 is an enlarged sectional front elevation of the shell support; Fig. 10 is a plan view of the same; Fig. 11 is an enlarged inverted plan view of the shank for holding the facing tool, and Fig. 12 is an enlarged inverted plan view of the facing tool.

On the base A' of a suitably constructed frame A, is arranged a shell support B for supporting the shell C, acted on by a tubular cutting tool or saw D and a facing tool E, to cut a portion out of the shell and to face the top portion of the cut-out portion, with a view to make a button. The shell C is held in place on the top of the shell support B during the cutting and facing operation, by a shell holder F, engaging the upper face of the shell adjacent to the tubular cutting tool D and on the side towards the tip of the shell, as plainly indicated in Fig. 2. The tubular cutting tool D is provided at its lower edge with suitable cutting teeth, and the said cutting tool is held within a tool holder G, in the form of a sleeve adapted to extend at its upper end centrally into a self-centering chuck H, having suitable gripping devices H' for engaging the upper end of the tool holder G to hold the same in place in the chuck.

The self-centering chuck H may be of any approved construction, but is preferably provided with a body H², containing the gripping devices H' and mounted to turn in the chuck H and casing H³, a spring H⁴ being interposed between the body H² and the casing H³, to return the casing H³ to normal position when temporarily held by the operator, for releasing the gripping devices H' while the body H² is turning. The chuck H is held on a Morse or other taper I, having a tapering head I' held by friction in engagement with a spindle J, mounted to slide up and down in a bearing A² on the main frame A, and in a barrel K held to slide in a bearing A³ in vertical alinement with the bearing A². A bevel gear wheel L is mounted to turn with and to slide on the spindle J near the upper end thereof, and the said bevel gear wheel L is in mesh with a bevel gear wheel L' secured on a shaft L² journaled in suitable bearings A⁴ arranged on the main frame A. On the shaft L² are arranged fast and loose pulleys L³ connected by a belt with other machinery, for imparting a continuous rotary motion to the shaft L², which by the bevel gear wheels L' and L rotates the spindle J and consequently the

shank I, the chuck II and the tool holder G carrying the tubular cutter D and the facing tool E. A spring O serves to feed the spindle J in a downward direction, and the 5 said spring O is coiled on the spindle J and rests with one end on the under side of the bearing A², and abuts with its other end on a washer O', resting on a ball bearing O², carried by a collar or a nut O³, screwing on 10 the spindle J and adapted to be secured thereto by a set screw O⁴. The tension of the spring O is regulated by adjusting the collar O³. The upper end of the spindle J is provided with fixed collars P, P' spaced 15 apart, and between the collars P, P' is loosely mounted a shifting collar P², having trunnions P³ engaging links P⁴, pivotally connected at their upper ends with an arm Q, secured on a shaft Q', journaled in suitable 20 bearings A⁵ arranged on the main frame A. On the shaft Q' is secured a downwardly extending hand lever Q² under the control of the operator, for imparting a turning motion to the shaft Q', so as to swing the 25 arm Q up or down, with a view to slide the spindle J in a like direction, for a purpose more fully explained hereinafter.

The tool holder G is provided near its upper end with oppositely disposed slots G', 30 engaged by lugs E' projecting from the head E² of the shank E³, removably carrying the facing tool E. The shank E³ extends above the upper end of the tubular cutting tool D, and the head E² is fitted to slide in the upper 35 portion of the tool holder G, as plainly shown in Fig. 3, to allow independent sliding motion of the tool holder G and the cutting tool D relative to the facing tool E, for a purpose hereinafter more fully described. The 40 facing tool E is cylindrical and of the same diameter as the shank E³, and the lower end of the facing tool E is preferably provided with a plurality of radially disposed cutting edges E⁴, for facing the portion of the shell 45 cut out by the cutting tool D, the said facing tool E being formed with a plurality of lengthwise extending apertures E⁵, fitting onto corresponding pins E⁶ depending from the shank E³ (see Figs. 11 and 12). Thus by 50 the arrangement described, the facing tool E turns with its shank E³ when the latter rotates with the tool holder G. The facing tool E is preferably provided with a recess E⁷ for the insertion of a centering bit if desired. 55

When the spindle J is running, the chuck H is rotated and with it the tool holder G in which the cutting tool D is removably secured, so that the cutting tool D rotates with the 60 tool holder G. But the facing tool E and the cutting tool D have a sliding movement, one relative to the other and in the direction of their common axis, that is, the tubular cutting tool D after cutting out a portion of 65 the shell C is caused to rise, while the facing

tool E is held against rising movement, so that the facing tool E acts as a punch to push out the cut out and faced shell portion, in case the latter sticks in the lower end of the cutting tool D.

For the purpose mentioned the top of the head E² is engaged by the lower end of a plunger R, having its upper end R' enlarged and fitted to slide centrally in the shank I (see Fig. 3). The plunger R extends centrally through a disk H⁶ held in the chuck H, and on the top of the said disk rests one end of a spring R², resting at its other end against the under side of the enlarged end R', so that the spring R² exerts an upward pressure on the plunger R. Through the upper end of the plunger R extends a pin R³, also passing through an elongated slot I² formed in the shank I, and the reduced ends R⁴ of the pin R³ engage recesses R⁵ formed in a sleeve R⁶, 80 adapted to engage with its upper end the under side of the cross head S, carrying the shell holder F and clampingly secured to the lower end of the barrel K previously referred to, and having a head K' adapted to 85 rest on top of the bearing A³. A spring S' is coiled on the lower end of the barrel K, and one end of the spring abuts against the cross head S, while the other end of the spring S' rests against the under side of the bearing A³, 90 to normally hold the barrel K and with it the cross head S in a lowermost position. When, however, the spindle J is raised by the operator swinging the hand lever Q² forwardly, then the shank I and the chuck H as 95 well as the sleeve R⁶, are raised to move the cutting tool D up out of the shell. The sleeve R⁶ abuts against the under side of the cross head S, so that the upward movement 100 of the sleeve R⁶ is limited, while the shank I and the chuck H move still farther upward with the spindle J. Now during the time the sleeve R⁶ is held against upward movement, the plunger R is likewise held against such movement, and consequently the facing 105 tool E, so that the cutting tool D slides upward on the facing tool E, and in case a cut-out shell portion sticks in the lower end of the cutting tool D, then the facing tool pushes it out of the same. 110

The shell holder F is provided with a presser foot F', adjustably secured by a set screw F² in the lower end of a rod F³, having its upper reduced portion F⁴ partly threaded and screwing in a quill T mounted to turn 120 and slide in the cross head S, previously referred to, and secured to the lower end of the barrel K. The upper terminal F⁵ of the rod F³ is mounted to slide in a bearing A⁶ attached to the bearing A³, and a spring U is 125 coiled on the reduced portion F⁴, and rests with its lower end on the quill T and abuts with its upper end against the under side of the bearing A⁶. The quill T is provided at its lower end with nuts T' extending a dis- 130

tance below the bottom of the cross head S, so as to allow a slight up and down movement of the quill T in the cross head S, the head of the quill T being normally seated on the cross head S by the action of the spring U. By the arrangement described the presser foot F' is adapted to engage the shell C at the tip thereof slightly in advance of the facing tool E, so as to hold the shell in position relatively to the supporting device B.

In order to support the tool holder G and the tools carried thereby in position in the self-centering chuck H, a slide V is provided, mounted to slide laterally on the under side of the chuck H, the slide V being preferably in the form of a dished disk, on the top of which is adapted to rest an annular shoulder or collar G² formed or secured on the tool holder G (see Fig. 3). The slide V is provided with a central opening V' of a diameter sufficiently large for the passage of the collar G², but this opening V' is normally eccentric to the tool holder G, as indicated in Figs. 3 and 6, for a portion of the collar G² to rest on the slide V.

The slide V is provided with elongated slots or guideways V² engaged by screws V³ screwing into the bottom of the chuck H, so as to hold the slide V in position on the chuck and to allow of shifting the same laterally to move the opening V' in or out of register with the collar G². A spring V⁴ serves to normally hold the slide V in the eccentric position, and this spring is secured at one end to the slide V, and is fastened at its other end to a lug H⁶ depending from the bottom of the chuck H.

When the several parts are in the position shown in Figs. 3 and 4, the tool holder G and the tools D and E carried thereby are supported by the slide V, and when it is desired to remove the tool holder G and the tools D and E then it is only necessary for the operator to press the slide V laterally against the tension of the spring V⁴ until the opening V' registers with the collar G², so that the tool holder G can slide downward out of the chuck H and the slide V. In a like manner the tool holder G with the tools D and E can be slipped in position in the chuck H, at the same time the slide V is in a concentric position relative to the chuck H. Now when the machine is running and it is desired to remove the tool holder G and the tools D and E for grinding, repairing or other purposes, then it is only necessary for the operator to temporarily take hold of the chuck casing H³, so as to cause the gripping device H' to release the tool holder G, and at the same time the operator presses the slide V laterally, to bring the opening V' in register with the collar G², so that the tool holder G is completely released and drops out of the chuck.

It is understood that the casing H³ of the self-centering chuck H has about a quarter-65 turn movement relative to the body H²

owing to the spring H⁴, and hence when the casing H³ is held against movement while the body H² turns, the gripping device H' is opened to release the tool holder G.

The support B for the shell C consists of a base B' attached to the frame base A', and in the base B' is mounted to slide a bearing B² in which screws a standard B³, in the upper end of which is mounted to turn a cap B⁴ having an inclined top and a flat side abutting against the flat face of an arm B⁵ rising from the base B'. A hook B⁶ on the arm B⁵ engages the base B' to hold the bearing B² against movement. By the arrangement described the standard B³ can be screwed up or down in the bearing B², to raise or lower the cap B⁴ held with its inclined top always in the same direction, as the cap B⁴ is held, against turning when screwing the standard B³ up or down. Thus by the arrangement described a very simple means is provided for bringing the inclined top of the cap B⁴ to the proper height for accommodating shells C of different thicknesses. The cap B⁴ is inclined on the top so that the butt end of the shell is at the lower portion of the cap, while the tip is at or near the upper portion to be engaged by the free end of the presser foot F' of the shell holder F, to bring the inner surface of the shell C into an approximately horizontal position. The upper face of the cap B⁴ is provided with an annular kerf B⁷ for the entrance of the lower end of the cutting tool D after cutting through the shell C.

The operation is as follows: When the machine is properly adjusted to commence cutting the button, the slide of the spindle J in the barrel K is set a proper distance between the head K' and the collar O³ on the spindle J, to cut the button and sever it from the shell when the tool has passed through the shell into the kerf in the lead cap B⁴. The slide in the quill T, between the cross head of the shell holder and the lock nuts T', is set at a proper distance for the free end of the presser foot F' of the shell holder F to be in advance of the facing tool E, also a sufficient distance to cover the distance the facing tool cuts into the shell. The shell-holding support B is then adjusted by screwing up the standard B³, until the lead cap B⁴ is up to the free end of the presser foot F' of the shell holder F, and the teeth of the cutting tool D run in the kerf in the lead cap B⁴. The sliding movement of the chuck shank I on the pin E³ is always equal or somewhat in excess of that of the movement of the spindle J, and the sliding movement at the top of the tool sleeve G is always equal or in excess of the movement of the shank I on the pin R³. The operation is then that when the spindle J is rotated and the hand lever Q² (see Fig. 1) is brought forward, then the spindle and with it the chuck H, tool holder G, the tools D and E and the shell holder F are raised.

The spindle is lifted the distance of the slide between the collar O^3 and the head K' , the latter always resting on the bearing A^3 until raised. The spindle being raised the distance between the collar O^3 and the head K' by the forward movement of the lever Q^2 , the cutting tool D is drawn up approximately flush with the facing tool E and the spring O is compressed an equal distance. Further forward movement of the lever Q^2 lifts the barrel K , and the spring S' is compressed and at the same time the shell holder F is raised, as its cross head S is attached to the barrel K and the springs U and J are also compressed the same distance. When the free end of the presser foot F' of the shell holder F is raised a sufficient distance to slide underneath it a shell, tip-end first, the operator releases the pressure on the lever Q^2 , while he still holds the shell C in the left hand, and the shell holder F and cutting tool D are let down upon the shell. The free end of the presser foot F' engages the shell C first, and the spring U is compressed until the facing tool E engages the shell C .

The distance the facing tool E cuts into the shell C , is the exact distance it is set to go when the lock nut at T' has closed the space and is against the cross head S , it being understood that the distance the facing tool cuts into the shell is regulated by adjusting the nut on the quill. For instance, if it is desired to cut into the shell one-sixteenth of an inch to face a button, the space between the nut T' and cross head S is preferably set at three-sixteenths of an inch, which advances the presser foot F' one-eighth beyond the facing tool E , but when the three-sixteenths space is closed, the facing tool E has advanced below the end of the presser foot F' one-sixteenth and would have faced the button. It is understood that the spring S' is a strong spring and the spring U a weak one, so that when the point of the shell holder which is in advance of the cutting tools engages the shell, the spring U will recede until the facing tool engages the shell. This movement is positive and never fails. The spring U is strong enough to hold the shell C , and the spring S' strong enough to force the facing tool E to face the button quickly, which is completed before the pressure of the spring O has forced the cutting tool D through the shell at the same time. The operator then completely releases the lever Q^2 and the operation of cutting and facing is automatic. When the shell holder F and cutting tool D have been set on the shell C , the operator releases his left hand from the shell C and the right hand from the lever Q^2 , and is now free to attend to another machine.

The saw or cutting tool is always slightly in advance of the facing tool, for the saw has an inside set on its teeth which the facing tool does not entirely pass through. The re-

sult is that the saw cutting tool attacks the shell slightly in advance of the facing tool, or rather the facing tool follows the cutting tool. It requires a greater length of time to cut through the shell than to face the button, so that the button is faced before the saw cuts through the shell, and severs the button from the shell. When it does cut through, the facing tool E has already gone the proper distance into the shell, and when the saw has passed through both spin harmlessly on the button until the lever is brought forward again, when the cutting tool slides up and the facing tool punches out the button should it have stuck in the end of the cutting tool D .

In cutting medium sized shells, which are seldom more than a quarter of an inch thick at the thickest place, the space between the head K' and the collar O^3 need not be more than one-fourth to three-eighths of an inch. The thickness of the shell from the tip to butt not varying in thickness more than one-eighth to three-sixteenths of an inch, it can be readily seen that the distance the shell holder F is to be raised from the lead cap B^4 need not be more than the distance necessary to slide the shell into place. The variation then in the thickness of the shell does not materially affect the pressing power of the springs.

The cap B^4 is preferably made of lead or other suitable soft material, so that the teeth of the cutting tool D are not liable to be injured when cutting through the shell, the cutting tool D at the first rise of the machine tending to cut circular kerfs B^7 into the top of the soft metal cap B^4 , so that when the cutting tool cuts through the shell C and enters the kerf, it is not liable to split or crack the bottom of the cut-out portion.

It is expressly understood that as the presser foot F' engages the tip of the shell C in advance of the facing tool E and cutting tool D , it is evident that the operator need not hold the shell in place on the cap B^4 of the shell support B during the cutting and facing operation.

By holding the shell C down onto the inclined face of the cap B^4 by the presser foot B' engaging the tip of the shell C , a perfect button is formed by the action of the cutting and facing tools D and E , as the irregularities in the surface of the shell are invariably rising toward the butt of the shell, so that the facing tool E can be readily set to cut down a certain depth below the point of contact between the tip of the shell C and the presser foot F' , with a view to produce a perfectly faced button.

It is further understood that by placing the shell C on the inclined surface of the cap B^4 , the inner surface of the shell is brought approximately into a horizontal position for the cutting tool D and the facing tool E to readily cut into the shell.

It is to be understood that by my machine the face of the button may be dressed to finish it, or dressed square to be finished by any other method, or a blank simply cut.

5 Having thus described my invention, I claim as new and desire to secure by Letters Patent:

1. An automatic button-cutting and shaping machine comprising a slidable spring-pressed barrel, a shell holder carried by the said barrel, a spindle for carrying the cutting and shaping tools, manually controlled means for raising and lowering the said spindle independent of the said barrel, and means 15 on the said spindle for raising the said barrel against the tension of its spring.

2. An automatic button-cutting and shaping machine provided with a spindle mounted to turn and to slide in the direction of its 20 axis, a chuck held on the said spindle, a tool holder held in the said chuck, a tubular cutting tool held in the said tool holder, a facing tool within the said tubular cutting tool, the cutting tool having movement independent 25 of the facing tool, and means for holding the said facing tool against movement while raising the said spindle, chuck, tool holder and cutting tool.

3. An automatic button-cutting and shaping machine provided with a tubular cutting tool mounted to turn and to slide in the direction of its length, means for raising and lowering said tool, a facing tool slidably mounted in the said tubular cutting tool and 35 adapted to turn with the same, and means for holding the said facing tool against sliding movement while sliding the said cutting tool.

4. An automatic button-cutting and shaping machine provided with a chuck, a tool holder held in the said chuck, a tubular cutting tool held in the said tool holder, means for raising and lowering the chuck, a facing tool slidably mounted in the said tubular 45 cutting tool and adapted to turn with the same, and means for holding the said facing tool against sliding movement while sliding the said tool holder and tubular cutting tool to cause the facing tool to act as a punch for 50 pushing a button out of the said tubular cutting tool.

5. An automatic button-cutting and shaping machine provided with a chuck, a tool holder held in the said chuck, a tubular cutting tool held in the said tool holder, a facing tool slidably mounted in the said tubular cutting tool and adapted to turn with the same, a shank on which the said chuck is secured, a spindle mounted to turn and to slide 60 in the direction of its axis and carrying the said shank, and means on the said chuck and spindle and coacting with a stationary part for holding the said facing tool against sliding movement on raising the said tubular cutting tool.

6. An automatic button-cutting and shaping machine provided with a chuck, a tool holder held in the said chuck, a tubular cutting tool held in the said tool holder, a facing tool slidably mounted in the said tubular 70 cutting tool and adapted to turn with the same, a shank on which the said chuck is secured, a spindle mounted to turn and to slide in the direction of its axis and carrying the said shank, a spring-pressed plunger slidably in the said shank and adapted to engage the said facing tool, and means for engaging the said plunger and holding it against movement while raising the said spindle, shank, 75 chuck and cutting tool.

7. An automatic button-cutting and shaping machine provided with a chuck, a tool holder engaged by the said chuck and having a flange and a slide held to slide laterally on the chuck and having an opening for the passage of the said tool holder, the said slide normally supporting the said flange and the said opening and flange being normally out of register, and when the said slide is shifted laterally the said opening registering with 80 the said flange, thus allowing the tool holder to drop out of the chuck when released by the latter.

8. An automatic button-cutting and shaping machine provided with a chuck having 95 gripping means, a tool holder adapted to be engaged by the said gripping means for the tool holder to turn with the said chuck, the said tool holder having a flange, means for releasing the tool holder from the gripping means of the chuck, and a spring-pressed slide mounted to slide laterally on the end of the chuck and having a central opening for the passage of the tool holder and normally eccentric thereto for the flange to rest on the 100 said slide, the latter when shifted laterally moving out of engagement with the said flange to allow the tool holder to drop on releasing the tool holder by the gripping device.

9. An automatic button-cutting and shaping machine provided with a shell holder comprising a spring-pressed support mounted to slide, a cross head secured on the said support, and a spring-pressed rod slidably 115 mounted on the said cross head and provided with a presser foot for engagement with the shell.

10. An automatic button-cutting and shaping machine provided with a shell holder 120 comprising a spring-pressed support mounted to slide, a cross head secured on the said support, a spring-pressed quill having a sliding movement in the cross head, a rod screwing in the said quill and carrying a presser foot for engagement with the shell, and means for raising or lowering the said support.

11. An automatic button cutting and shaping machine provided with a slidable 130

- tool holding sleeve having slots at its upper end, a tubular cutting tool held in the sleeve, a facing tool fitted to slide in the tubular cutting tool and having at its upper end a head 5 provided with pins working in the slots of the said sleeve, means for sliding the sleeve and cutting tool, and means for holding the facing tool against movement when the sleeve and cutting tool are slid.
- 10 12. An automatic button - cutting and shaping machine provided with a tool holding sleeve having slots at its upper end, a tubular cutting tool held in the said sleeve, a facing tool fitted to slide in the said tubular 15 cutting tool and having a head slidable in the said sleeve, the head having lugs slidingly engaging the said slots, a slidable chuck carrying the said tool-holding sleeve and rotating it and the tools carried thereby, a spring- 20 pressed plunger working in the chuck and engaging the head of the facing tool, means for sliding the said chuck, and means for preventing the plunger from partaking of the retractile movement of the chuck.
- 25 13. An automatic button - cutting and shaping machine provided with a tool-holding sleeve having slots at its upper end, a tubular cutting tool held in the said sleeve, a facing tool fitted to slide in the said tubular 30 cutting tool and having a head slidable in the said sleeve, the head having lugs slidingly engaging the said slots, a slidable chuck carrying the said tool-holding sleeve and rotating it and the tools carried thereby, a spring- 35 pressed plunger working in the chuck and engaging the head of the facing tool, means for sliding the chuck, and means for limiting the movement of the plunger with respect to the chuck.
- 40 14. An automatic button - cutting and shaping machine provided with a spindle, a tool holder for engagement by the gripping means of the said chuck, and movable means on the chuck for supporting the said tool holder and for disengaging the same, to allow the tool holder to drop out of the chuck on releasing the tool holder from the gripping means.
15. An automatic button - cutting and 50 shaping machine comprising a spindle, means for rotating the spindle, manually controlled means directly connected with the said spindle for raising and lowering the latter, a self-centering chuck on the said spindle, a tool holder for removable engagement with the said chuck, and a shell holder having a spring-pressed barrel mounted to slide on the spindle independent of the latter, a cross head on the said barrel, and a spring-pressed rod carrying 55 60 a presser foot and slidably connected on the said cross head.
16. An automatic button - cutting and shaping machine comprising a spindle, means for rotating the spindle, manually controlled 65 means directly connected with the said spin-
- dle for raising and lowering the latter, a self-centering chuck on the said spindle, a tool holder for removable engagement with the said chuck, and a shell holder having a spring-pressed barrel mounted to slide on the spindle 70 independent of the latter, a cross head on the said barrel and a spring-pressed rod carrying a presser foot and slidably mounted on the said cross head, and means on the said spindle for engagement with the said barrel to 75 raise the latter against the tension of its spring.
17. An automatic button cutting and shaping machine, comprising a sliding and spring pressed spindle, means for rotating 80 the spindle, manually controlled means for raising and lowering the spindle, a tool holder carried by the spindle, a sliding and spring pressed barrel in which the spindle slides, and an adjustable and spring pressed shell holder 85 carried by the barrel.
18. An automatic button cutting and shaping machine, comprising a sliding and spring pressed spindle, means for rotating 90 the spindle, means for raising and lowering said spindle, a chuck carried by the spindle, a tool holder carried by the chuck, a sliding and spring pressed barrel in which the spindle slides, and an adjustable and spring pressed shell holder carried by the barrel. 95
19. In a button cutting machine, a spindle, a tool holder carried by the spindle, a barrel in which the spindle slides, said barrel having a laterally projecting member, a sliding and spring pressed shell holder carried by the said 100 member, and means for limiting the sliding movement of the shell holder.
20. In a button machine, a spindle, a tool holder carried by the spindle, a barrel in which the spindle slides, said barrel having a cross 105 head, a tubular member slidably mounted in the cross head, means for regulating the sliding movement of said tubular member, a shell holder secured in the tubular member, and a spring surrounding the shell holder and 110 normally holding the tubular member in its lowermost position.
21. In a button cutting machine, a spindle, a tool holder carried by the spindle, a sliding barrel in which the spindle slides, said 115 barrel having a cross head, a spring surrounding the barrel and normally pressing the cross head into its lowermost position, a tubular member slidably mounted in the cross head, means for limiting the sliding movement of the tubular member, a shell holder carried by the tubular member, and a spring surrounding the shell holder and normally holding the tubular member in its lowermost position, the spring of the barrel being 120 stronger than the spring of the shell holder. 125
22. In a button machine, a spindle, a sliding and spring pressed barrel having a cross head and in which the spindle slides, a shell holder carried by the cross head, a chuck, a 130

shank connecting the chuck with the spindle, a spring pressed plunger sliding in the shank and extending into the chuck to engage the shank of a tool carried by the chuck, and a 5 member carried by the plunger and engaging the cross head.

23. In a button machine, a spindle, a sliding and spring pressed barrel in which the spindle slides, said barrel having a cross head, 10 a shell holder carried by the cross head, a chuck, a slotted shank connecting the chuck with the spindle, a spring pressed plunger sliding in the shank and extending into the chuck to engage the shank of a tool carried thereby, said plunger having at its upper end 15 a transverse pin working in the slot of the connecting shank, and a sleeve with which

the said pin engages, said sleeve engaging the cross head of the barrel.

24. In a button machine, a tubular tool 20 holder, a tubular cutting tool in the holder, a shank in the tubular cutting tool and having interlocking engagement with the tool holder, said shank having a plurality of pins at its lower end, and a facing tool, within the cutting tool and having a plurality of apertures to receive the pins of the shank.

In testimony whereof I have signed my name to this specification in the presence of two subscribing witnesses.

WINFIELD SCOTT WATSON.

Witnesses:

VERA WATSON,
HELEN WATSON.
